UNITED STATES PATENT OFFICE

108,554

DESIGN FOR A PHOTOGRAPHIC ENLARGER

Rudolph Simmon, Long Island City, N. Y.

Application November 27, 1937, Serial No. 73,228

Term of patent 7 years

To all whom it may concern:

Be it known that I, Rudolph Simmon, a citizen of the United States, residing in Long Island City, county of Queens, State of New York, have invented a new, original, and ornamental Design for a Photographic Enlarger, of which the following is a specification, reference being had to the accompanying drawings, forming a part thereof, in which:

The figure is a perspective view of a photographic enlarger showing my new design.

I claim:

The ornamental design for a photographic enlarger substantially as shown.

RUDOLPH SIMMON.
